UNITED STATES PATENT OFFICE.

CARL G. HEIBY, JOHN BURKAM, DAVID E. LINDQUIST, FRED L. RIGGIN, EBENEZER W. ALLEN, AND RICHARD LAU, OF SARNIA, ONTARIO, CANADA, ASSIGNEES, BY MESNE ASSIGNMENTS, TO MUELLER METALS COMPANY, OF PORT HURON, MICHIGAN, A CORPORATION OF MICHIGAN.

BLANK FOR AND METHOD OF MAKING FUSE-BODIES.

1,393,121.

Specification of Letters Patent. Patented Oct. 11, 1921.

Application filed January 17, 1918. Serial No. 212,226.

To all whom it may concern:

Be it known that we, CARL G. HEIBY, JOHN BURKAM, DAVID E. LINDQUIST, FRED L. RIGGIN, EBENEZER W. ALLEN, and RICHARD LAU, all citizens of the United States, except ALLEN, a subject of Great Britain, residing at Sarnia, in the county of Lambton and Dominion of Canada, have invented new and useful Improvements in Blanks for and Methods of Making Fuse-Bodies, of which the following is a specification.

The present invention relates to improvements in forgings, and methods of finishing the same, and as herein disclosed is shown as applied to forgings for fuse bodies, such as are used in arming shells, these fuse bodies carrying fuses of any desired type, not uncommonly of the type known as "time fuses."

It has for its object to provide a body which is forged into substantially its final form and which is so fashioned that it may be readily chucked in a lathe or other finishing machine when it is subjected to machining and finishing.

By the practice of our invention the delay, expense and waste incident to completely machining the slugs or stock from which the final fuse body is made, is done away with, so that production is increased, waste largely eliminated, and cost of making is very substantially reduced.

While we have disclosed in the accompanying drawings several types of forgings, it will be understood that we do not restrict our invention to the specific embodiment shown, as it is obvious that the shape of the fuse bodies may be varied without departing from the principle of our invention, and, furthermore, the invention may be practised in connection with articles other than the fuse bodies herein shown.

In the drawings herewith:

Figure 1 is a perspective view of the stock or slug from which the blank is forged, and these slugs may be produced, of course, in any desired way, and of the proper dimensions for the work in hand.

Fig. 2 is a view in side elevation of a fuse body forged from the slug shown in Fig. 1.

Fig. 3 is a view in vertical section of the forging shown in Fig. 2.

Fig. 4 is a view in side elevation of a finished fuse body formed from the forging shown in Figs. 2 and 3.

Fig. 5 is a view in vertical section of the finished body shown in Fig. 4, illustrating conventionally the arming passages and channels to receive the fuse elements.

Fig. 6 is a view in side elevation of a slightly different form of forging.

Fig. 7 is a view in side elevation of a portion of the blank showing the chucking surface arranged between the top and base of the conical portions.

Referring to the drawings by numerals, like numbers indicating like parts in the several views, 10 indicates the slug or stock from which the forgings may be conveniently formed. Thus slug 10 is shown, in the present instance, as cylindrical, and it may be formed in any desired way, being of the dimensions necessary to provide stock enough for the particular fuse body which is to be formed therefrom. The said slug 10 is heated to the desired temperature, and is then subjected to the action of a forging press, which brings it to the form shown in Fig. 2, with a coned portion 11, a cylindrical upper portion 12, and a substantially cylindrical lower part 13 of less diameter than the portion 11. The action of the forging press upon the slug 10 is such that while it brings it to substantially the form shown in Fig. 2, there will be a small amount of excess metal in the form of a projecting circular fin 13' (shown in dotted lines in Fig. 2), which, in the present instance, projects from the forging at substantially the bottom of the cone portion 11, although its location may vary, as it is dependent on the particular relation of the press members.

This fin 13' will, of course, be trimmed off, and this may be readily and economically done, as the metal is thin at the point of juncture of the fin with the body, and these trimmings can be remelted and utilized without any appreciable loss. It will be seen that the forging shown in Fig. 2 has substantially the final form, so far as external shape is concerned, as the finished fuse body shown in Fig. 4, and in order to further reduce the finishing operations we preferably forge in the end of the portion

12 of the body a recess 14, and the bottom portion 13 has a recess 15, and these forged recesses materially reduce the labor of machining, as they do away with the necessity 5 of cutting out on a lathe, or other metal working machine, the material which must be removed to provide these necessary cavities.

The forging shown in Figs. 2 and 3, is, 10 as stated, substantially at its final form, and furthermore, it is of such contour that either the portion 12 or the portion 13 may be readily inserted and held in the chuck of the finishing machine, for boring and finish- 15 ing operations.

It will be seen that the conical section 11 of the forging is, as stated, of substantially the final form in the finished body, but the forging may be readily held in the chuck 20 of the finishing machine for the operations which are necessary on the bottom portion 13, by means of the cylindrical portion 12, and the lower part 13 may be used as a chucking surface when the opposite end of 25 the forging is to be finished. After the several finishing operations to which the article is subjected have been completed, it will have been brought to the final form, except for the cylindrical portion 12, and this cylindrical portion will then be machined off 30 along the dotted line indicated in Fig. 2, so as to complete the conical body portion 11, as appears in the finished forging, Fig. 4, and it is apparent that the amount of 35 machining necessary to remove this small section is very slight, and, furthermore, that there is but little waste in connection with this finishing operation.

It will be observed that the cavity 14, 40 which is forged in the top of the cone, is of substantially the size and area of the screw-threaded seat, so that the necessity of machining this portion out is eliminated. The same is true of that cavity 15 formed in the 45 bottom portion 13 of the forging.

In Fig. 6 is shown a slightly different form of forging from that shown in the other views. While of the general outline of that body heretofore described, in that it 50 has a conical portion 16 and a bottom portion 17, the chucking surface is at the base of the cone 16 instead of at its top, as in the other forms, this chucking portion 18 being shown as cylindrical and serving as a convenient gripping means for the chuck during the finishing operations on the bottom portion 17. Except for the shifting of the cylindrical surface 18 from the top of the cone to the bottom, the forging will be as 55 heretofore described, with the forged recesses in the top and bottom thereof, as indicated in dotted lines. After the several 60 finishing operations, necessary to the formation of the fuse body, are completed the 65 chucking surface 18 will be machined off to

the dotted line shown in Fig. 6, thus extending the conical surface 16, and bringing the body to the final form shown in Fig. 4.

We have disclosed in Figs. 2, 3 and 6, two arrangements of chucking surfaces on the 70 coned portion of the forging. In Figs. 2 and 3, the surface 12 is at the top of the coned portion; while in Fig. 6, it is at the base of this cone. It will be obvious that this cylindrical chucking surface may be conveniently arranged at any point along the cone and fulfil the requirements. For example, in Fig. 7, there is indicated a chucking surface 18' which is between the top and bottom of the cone portion 16, and we do 75 not, therefore, limit ourselves to any particular location of this chucking surface lengthwise the cone, as it may be variously disposed thereon with good results.

In the foregoing description the word 80 "forging" has been used in referring to the article in question, but it will be understood, as stated at the outset, the body may be formed by casting instead of forging, without departing from the invention set forth. 85

Furthermore while we have shown the chucking surfaces in the disclosures herein as substantially cylindrical in form, it will be evident that the invention is not limited to making this part of any particular form, 90 and still be within the range of our invention.

We claim:—

1. As a new article of manufacture, a blank for fuse bodies and the like having 100 between its ends a chucking surface which is adapted to be machined off or finished after the blank has been subjected to other finishing operations.

2. As a new article of manufacture, a 105 blank for fuse bodies having a portion shaped to substantially conical form, and provided with a chucking surface removed from the tip of said conical portion, which chucking surface is adapted to be machined off or finished after the forging has been 110 subjected to other finishing operations.

3. The method of forming fuse bodies which consists in forging a body with a portion thereof of substantially the conical shape of the finished body, and with a chucking surface adjacent the base of the cone; subjecting said body to finishing operations; and afterward machining off said chucking 115 surface to complete the cone. 120

4. The method of forming fuse bodies which consists in forging a body with a portion thereof of substantially the conical shape of the finished body, and with a cylindrical chucking surface removed from the 125 end of the cone; subjecting said body to finishing operations; and afterward machining off said cylindrical chucking surface to complete the cone.

5. The method of forming fuse bodies 130

which consists in forging a body with a portion thereof of substantially a conical shape of the finished body, and with a cylindrical chucking surface located at a point removed 5 from the apex of the cone; subjecting said body to finishing operations; and afterward machining off said cylindrical chucking surface to complete the cone.

In testimony whereof we have hereunto set our hands.
